DESIGN FOR A TOWEL DISPENSING CABINET

Howard B. Lewis, Inglewood, Calif., assignor to Towlsaver, Inc., Los Angeles, Calif., a corporation of California

Application October 25, 1940, Serial No. 96,982

Term of patent 14 years

To all whom it may concern:

Be it known that I, Howard B. Lewis, a citizen of the United States, residing at Inglewood, in the county of Los Angeles and State of California, have invented a new, original, and ornamental Design for a Towel Dispensing Cabinet, of which the following is a specification, reference being had to the accompanying drawing, forming part thereof.

In said drawing:

Fig. 1 is a front elevation;
Fig. 2 is an end elevation;
Fig. 3 is a top plan view; and
Fig. 4 is a perspective view of a towel dispensing cabinet, showing my new design.

I claim:

The ornamental design for a towel dispensing cabinet, as shown.

HOWARD B. LEWIS.
